UNITED STATES PATENT OFFICE

GUSTAV PALME, OF STREHLA-ON-THE-ELBE, GERMANY

GLUE PRODUCT

Application filed January 16, 1928. Serial No. 247,047.

My invention refers to glue and gelatine and its particular object is to provide a new and improved product of the kind aforesaid having properties which render it particularly convenient for practical use.

The glue products hitherto on the market differ widely in character. The oldest and best known product has the form of plates or slabs and it is a well known fact that in this form the glue will dissolve in hot water only after a number of hours or even days. Obviously this involves a considerable loss of time to the consumer, and if great quantities of glue are required for immediate use, disturbances in operation may arise in view of the difficulty of preparing fresh glue ready for use.

In view of these drawbacks it has already been suggested to provide glue in comminuted form in order to reduce the time of dissolution. Thus for instance glue powder has been produced by breaking and milling the large plates or slabs. It has further been proposed to atomize solutions of glue, the particles of liquid being then dried to form an exceedingly fine powder. Another method consists in reducing glue solutions to spherical or drop-shaped bodies. All these small-sized products are capable of taking up water quickly and therefore require less time for swelling and dissolving than the larger slabs or plates hitherto used. However, these products lack certain outward characteristics to be found in these slabs or plates, which have always been instrumental in ascertaining the quality and more especially the purity of the glue. The consumers, such as carpenters and the like, are known to rely, apart from the colour, brightness and transparency, also on the form of the edges of a plate of glue as affording the possibility of judging the quality of the product. Powdered glue lacks all these characteristics and is further liable to being adulterated without it being possible to ascertain such adulterations outside of the chemical laboratory. The small spherical bodies of glue which are to be found on the market, while being bright and transparent, do not show the characteristic edges.

The present invention refers to a form of glue, which has all the outward characteristics of the large plates or slabs, including the typical formation of edges, while offering to the solvent a far greater surface per unit of weight so that it will swell and dissolve rapidly. The product according to the present invention has the form of small-edged polygonal bodies which may either form cubes or polyeders or star-shaped bodies or the like, their sizes ranging for instance between the size of a finger nail and of a millet-grain.

In the drawings affixed to this specification and forming part thereof a few characteristic forms of bodies embodying my invention are illustrated by way of example.

Fig. 1 shows a quadrangular,

Fig. 2 a hexagonal slab,

Fig. 3 a star-shaped body, all of them being shown substantially of the largest size contemplated by this invention, which however also includes similar bodies measuring only one tenth or one twentieth.

Small bodies of this shape can be produced for instance by forming a jelly from glue swollen in water and introducing this jelly into a centrifugal apparatus, the rotary wall of which is perforated by rectangular, polygonal, star- or otherwise shaped holes. By the action of the centrifugal force the jelly is forced through these holes and will project therefrom in the form of strips having substantially the cross-section determined by the form of the holes. By means of stationary cutters contacting with the outer surface of the rotary centrifugal drum these strips can be subdivided into thin cuttings which are then dried in the usual manner.

I wish it, however, to be understood that bodies such as claimed in the appended claim can also be produced in various other ways and I do not wish to be limited to the particular mode of producing same as above described.

The term "glue" as used in the appended claim is intended to include also gelatine.

I claim:

A glue product having the form of a polygonal shaped body, the area of which does

not substantially exceed the size of a finger
nail, having a plurality of edgewise projec-
tions that are reduced in width toward their
free ends to provide a series of edges which
5 will aid a user in determining the quality of
the product.

In testimony whereof I affix my signature.
GUSTAV PALME.
